SAND SEPARATOR FOR DEEP WELLS

George S. Fosnaugh, Compton, Calif.

Application February 13, 1940, Serial No. 318,725

10 Claims. (Cl. 103—204)

This invention relates to a separator to be used at the bottom of a well for effecting the separation of sand from a liquid, such as oil, that may carry a considerable quantity of sand with it. As is well known, when sand is present in a liquid being pumped, it is destructive to the valves and the pump plunger or piston, as it will score the valves and valve seats, eventually increasing the leakage to such an extent that the valves must be renewed.

A principal object of this invention is to provide a sand separator for use at the bottom of the well, that will operate to remove a large proportion of the sand carried in the liquid being pumped. In carrying out the invention, means is provided for developing a current in the incoming liquid with which sand ejecting means cooperates to separate the sand and eject it from the liquid; and one of the objects of the invention is to provide means for insuring that the separator device will not eventually become packed with sand.

A further object of the invention is to provide automatic means for ejecting any sand that might accumulate in the separator beyond the separating devices that operate successively to extract the sand from the flowing current of liquid.

Further objects of the invention will appear hereinafter.

The invention consists in the novel parts and combination of parts to be described hereinafter, all of which contribute to produce an efficient sand separator for deep wells.

A preferred embodiment of the invention is described in the following specification, while the broad scope of the invention is pointed out in the appended claims.

In the drawing:

Fig. 1 is a side elevation of the lower end of the flow pipe to which my invention is applied.

Fig. 2 is a front elevation of my sand separator upon a larger scale, and representing the same as removed from the lower end of the flow pipe.

Fig. 3 is a vertical section taken about on the line 3—3 of Fig. 2, and particularly illustrating the details of the construction on the interior of the separator.

Fig. 4 is a cross-section upon a still larger scale, and taken on the line 4—4 of Fig. 2.

Fig. 5 is a cross-section similar to Fig. 4, but taken on the line 5—5 of Fig. 2.

Fig. 6 is a horizontal cross-section taken on the line 6—6 of Fig. 2.

In practicing the invention, I provide a tubu-

lar body 1, which is constructed so that it can be readily attached to the lower end of a flow pipe 2. While this improvement can be employed with any kind of a pump that develops an upward flow through the bottom of a flow pipe, in the present specification I have described the invention as applied to a deep well pump of common construction, having a standing valve 3, and a reciprocating pump rod 4 carrying a piston 5 with a valve 6.

In accordance with my improvement, I construct the tubular body 1 with means for developing a downward flowing current of the sand carrying liquid, and I provide means operating on this downward current to effect the separation of the sand from the liquid. In the present instance, I provide the tubular body 1 with a substantially vertical partition wall 7 that may, if desired, be located near the central axis of the tubular body. This partition wall divides the interior of the body where it is located, into a down-take duct 8 and an up-take duct 9. When the suction occurs that draws the liquid into the separator, for example, during the up-stroke of the pump rod 4, a partial vacuum will be developed in the duct 9, up which the liquid will flow. Throughout the length of the down-take duct 8, I provide a plurality of means for effecting the separation of the sand from the flowing liquid.

In order to accomplish this, I prefer to provide an elbow-shaped inlet 10, which has a mouth 11 emerging through the outer wall of the body at this point. This elbow inlet directs the inflowing liquid in a downward direction, and as the liquid passes downwardly, it passes a series of baffles 12. These baffles are preferably in the form of inclined webs 13 that may be formed integrally with the outer wall of the body, and inclined so that they will guide the sand outwardly through sand outlets 14. These sand outlets 14 are preferably of larger diameter toward the upper end of the separator, so that they gradually decrease toward its lower end. These baffles nearly block the passage for the liquid, but their inner edges are disposed slightly away from the plate-like partition 7 so that a series of slots 15 are formed in the separator, and these slots are of gradually increasing width toward the lower end of the separator.

At the lower end of the duct 8 the liquid passes through, or under, the lower edge of the partition 7, and thence upwardly as indicated by the arrows at this point. In the operation of the device, the sand coming down with the current in the down-take duct, is deflected outwardly by

the baffles, but of course as this sand is ejected, a considerable quantity of the liquid will pass out with the sand. I provide means for returning this liquid, and this means preferably consists of a plurality of small liquid inlets 18. In this way, in the operation of the device, a kind of local circulation of the liquid is developed at the bottoms of the baffles, with the liquid passing in through the liquid inlets 18 and the sand passing out. These inlets 18 operating in this way, tend to prevent any possible clogging of the sand in the sand outlets, and at the bottoms of the inclined baffles.

Of course, some sand will remain in the liquid passing under the bottom edge of the partition 7, and unless some provision were made for eliminating this sand, the separator will eventually clog up at this point. On this account, I provide an automatic sand ejector which preferably involves the use of an ejector valve 19 that comes upwardly upon the valve seat formed in a web or wall 20 extending across the interior of the body. Just above this valve, I prefer to provide a rotary device 21, which operates as an agitator. This is in the form of a bladed wheel mounted to rotate in a substantially vertical plane. This wheel is located slightly below the junction point of the down-take duct 8 and the up-take duct 9.

The valve is held on its seat by a light coil spring 22. If any sand tends to accumulate at this point, it will be ejected eventually when the valve 19 opens. Of course, the momentum of the sand coming down the down-take duct 8 will have some influence on bringing this result about, but the same result is augmented at the commencement of the down-stroke of the piston, because when this occurs, of course the suction condition in the duct 9 changes into a slight pressure condition accompanied by a back surge of the liquid that opens the valve, and also rotates the agitator due to the curvature of its blades. This increase of pressure will tend to open the valve occasionally, if not on every stroke of the pump, and the sand will pass down into a sand chamber 23 below the valve from which sand can pass outwardly through an outlet 24 in the side of this sand chamber. The valve 19 may be guided in any suitable manner, and may include a long stem 25, the lower end of which is guided in the plug 26 that screws into the lower end of the separator.

The agitator 21 includes outwardly projecting blades 27. The rotation of this agitator would be in an anti-clockwise direction, so that the blades 27 would tend to prevent the sand carried in the liquid that passes under the partition, from rising, and throwing the same toward the left, as viewed in Fig. 3.

For convenience in manufacture, the baffles may be carried on a section or cover 1a that can be welded in place or otherwise secured.

Many other embodiments of this invention may be resorted to without departing from the spirit of the invention.

What I claim is:

1. In a liquid and sand separator for use at a well bottom, the combination of a tubular body to be attached to the lower end of the flow pipe of the well, and having a substantially vertical partition wall dividing the same into an up-take duct, and a down-take duct with its upper end closed off above from communication with the interior of the tubular body, means for admitting the liquid in a current carrying sand adjacent the upper end of the down-take duct, and for di-

recting the sand current downward, the pumping suction in the up-take duct operating to maintain the downward movement of the said current, the outer wall of said down-take duct having sand outlets, and baffles projecting across the current in the down-take duct and past which the said current flows downward, for baffling the sand and for guiding the same out through said sand outlets while permitting the liquid in said current to pass.

2. In a liquid and sand separator for use at a well bottom, the combination of a tubular body to be attached to the lower end of the flow pipe of the well, and having a substantially vertical partition wall dividing the same into an up-take duct, and a down-take duct with its upper end closed off above from communication with the interior of the tubular body, means for admitting the liquid in a current carrying sand adjacent the upper end of the down-take duct, the pumping suction in the up-take duct operating to maintain the downward movement of the said current, the outer wall of said down-take duct having sand outlets, and a plurality of inclined baffles located at different levels with respect to each other, projecting from the outer wall of the down-take duct, inclining downwardly toward their outer ends for arresting the sand and for guiding the same out through said sand outlets.

3. In a liquid and sand separator for use at a well bottom, the combination of a tubular body to be attached to the lower end of the flow pipe of the well, and having a substantially vertical partition wall dividing the same into an up-take duct, and a down-take duct with its upper end closed off above from communication with the interior of the tubular body, means for admitting the liquid in a current carrying sand adjacent the upper end of the down-take duct, the pumping suction in the up-take duct operating to maintain the downward movement of the said current, the outer wall of said down-take duct having sand outlets, and inclined baffles projecting inwardly into the down-take duct from the outer wall thereof, inclining downwardly toward the outer wall for arresting the sand and for guiding the same out through said sand outlets, the inner edges of said baffles being progressively at greater distances from the said partition wall toward the lower end of said down-take duct.

4. In a liquid and sand separator for use at a well bottom, the combination of a tubular body to be attached to the lower end of the flow pipe of the well and having a substantially vertical partition wall dividing the same into an up-take duct, and a down-take duct with its upper end closed off above from communication with the interior of the tubular body, the upper end of said down-take duct having an inlet for the sand carrying liquid for delivering the same in a downward direction through the down-take duct, a plurality of separating means disposed along the down-take duct operating to arrest portions of the sand and direct the same out of the down-take duct, said parts cooperating so that the liquid passes by the partition below the sand separating devices and flows upwardly toward the flow pipe, and a rotary device in said tubular body below the point where the liquid passes the plane of said partition, said rotary device being rotated by the flowing liquid and having outwardly projecting blades for baffling any sand still remaining in the liquid current.

5. In a liquid and sand separator for use at a well bottom, the combination of a tubular body

to be attached to the lower end of the flow pipe of the well and having a substantially vertical partition wall dividing the same into an up-take duct, and a down-take duct with its upper end closed off above from communication with the interior of the tubular body, the upper end of said down-take duct having an inlet for the sand carrying liquid for delivering the same in a downward direction through the down-take duct, a plurality of separating means disposed along the down-take duct operating to arrest portions of the sand and direct the same out of the down-take duct, said parts cooperating so that the liquid passes by the partition below the sand separating devices and flows upwardly toward the flow pipe, a rotary device in said tubular body below the point where the liquid passes the plane of said partition, said rotary device being rotated by the flowing liquid and having outwardly projecting blades for baffling any sand still remaining in the liquid current, and a valve below the rotary device including means for exerting a light pressure to hold the same closed, said valve operating to open from time to time and permit accumulating sand to pass downwardly and out of said tubular body.

6. In a liquid and sand separator for use at a well bottom, the combination of a tubular body to be attached to the lower end of the flow pipe of the well, and having a substantially vertical partition wall dividing the same into an up-take duct, and a down-take duct with its upper end closed off above from communication with the interior of the tubular body, means for admitting the liquid in a current carrying sand adjacent the upper end of the down-take duct, the pumping suction in the up-take duct operating to maintain the downward movement of the said current, the outer wall of said down-take duct having sand outlets, baffles in the down-take duct for arresting the sand and for guiding the same out through said sand outlets, the outer wall of said down-take duct having liquid inlets relatively smaller than the said sand outlets.

7. In a liquid and sand separator for use at a well bottom, the combination of a tubular body to be attached to the lower end of the flow pipe of the well, and having a substantially vertical partition wall dividing the same into an up-take duct, and a down-take duct with its upper end closed off above from communication with the interior of the tubular body, means for admit-

ting the liquid in a current carrying sand adjacent the upper end of the down-take duct, the pumping suction in the up-take duct operating to maintain the downward movement of the said current, the outer wall of said down-take duct having sand outlets of relatively larger area toward the upper end of said down-take duct, and a progressively smaller area toward the lower end of the down-take duct, and baffles in the down-take duct for arresting the sand and for guiding the same out through said sand outlets.

8. In a sand separator for a deep well, to be attached to the flow pipe, the combination of a down-take duct through which the sand and liquid descends, an up-take duct with which the lower end of the down-take duct communicates, for directing the liquid upward, a movable mechanical agitator mounted at the junction of the lower ends of the ducts, so as to be rotated by the current passing between the ducts, and down past the agitator, and an ejector sand valve therebelow.

9. In a sand separator for a deep well, to be attached to the flow pipe below a pump, the combination of a casing having a down-take duct through which the current of liquid carrying sand descends, and an up-take duct with which the lower end of the down-take duct communicates for directing the liquid upwardly, an agitator located adjacent the lower ends of the ducts and having blades in the path of the descending liquid and operating to be rotated by the passing current due to the increase in pressure accompanying the down stroke of the pump; and an ejector sand valve therebelow adapted to be opened by the said increase in pressure.

10. In a sand separator for a deep well, to be attached to the flow pipe below a pump, the combination of a casing having a down-take duct through which the current of liquid carrying the sand descends; an uptake duct with which the lower end of the down-take duct communicates for directing the liquid upward, an agitator in the form of a bladed wheel mounted to rotate in a substantially vertical plane adjacent to, and below, the junction point of said ducts so that the blades of the wheel lie adjacent the path of the descending sand, said blades being bent and cooperating with the flow of the current to rotate the wheel, and an ejector sand valve below the agitator.

GEORGE S. FOSNAUGH.
